UNITED STATES PATENT OFFICE.

CHARLES RUDOLPH CARLETON, OF BROOKLYN, NEW YORK.

FILM CLEANING AND POLISHING MACHINE.

1,405,277.

Specification of Letters Patent. Patented Jan. 31, 1922.

Application filed October 13, 1919. Serial No. 330,177.

To all whom it may concern:

Be it known that I, CHARLES R. CARLETON, a citizen of the United States, and a resident of the city of New York, borough of Brooklyn, in the county of Kings and State of New York, have invented a new and Improved Film Cleaning and Polishing Machine, of which the following is a full, clear, and exact description.

10 This invention relates to a machine for treating continuous strips of material and has reference more particularly to a machine for polishing or cleaning continuous strips of motion picture films.

15 The primary object of the invention is to produce a machine of the character described which may be used for polishing newly made films or for cleaning old or used films and particularly the emulsion side 20 of the films without injury to the sensitized surface.

Further objects will appear upon reference to the accompanying drawings in which—

25 Figure 1 is a front elevation of the machine.

Fig. 2 is a rear elevation.

Fig. 3 is a top plan view.

30 Fig. 4 is a cross section through the axis of the main drive.

Fig. 5 is a side view of one of the buffers.

Fig. 6 is a sectional view of one of the moistening rollers, the fluid supply thereto being shown in elevation.

35 Fig. 7 is a sectional view through the axis of one of the feed sprockets.

Fig. 8 is a cross section through the take-up magazine; and

40 Fig. 9 is a like view through the supply magazine.

Referring to the drawings in detail 1 represents a suitable table or supporting frame on which may be mounted a driving motor (not shown) or the motor may be otherwise mounted. Supported upon the table 1 is the machine frame 2 which is constructed with the usual standards, etc., to be later referred to. Inasmuch as the work to be performed by the machine involves the treatment of a so-called continuous strip of film the machine is equipped with a pair of magazines 3 and 4 from which the film is supplied to and recovered from the treating apparatus, thus the magazine 3 becomes the supply and magazine 4 the take-up. Both magazines are suspended by means of the downwardly

presented hangers 3^a and 4^a having journal bearings 3^b and 4^b for the spindles 3^c and 4^c whereby a reel of film may be rotatably supported in the respective magazines with 60 freedom of rotation. The film is represented at A and is adapted to be delivered through a radial slot in the rim of the supply magazine 3, which slot is provided with a pair of opposed rollers 3^d. From the 65 supply magazine the film is delivered over the first feed sprocket then over the moistening rollers 6 which are rotatably mounted in the same plane on the horizontal arm 7. Tension rollers 8 and 8^a being mounted also 70 in the horizontal arm 7 intermediate the moistening rollers 6 and on the opposite side of the last moistening roller to insure contact of the film with the wicks of the rollers which supply the necessary cleaning fluid 75 to the under side of the film. When the film has been thus subjected to the cleaning fluid it passes over another tension roller as at 8^b then through the buffing process which is accomplished preferably by means of a plurality of buffers 9, 9^a and 9^b, all three of which are rotatably mounted in the same plane with idler wheels 10, 10^a and 10^b supported with freedom of rotation above the buffers so that the film will be maintained 80 not only in contact with the buffers but also feed past the buffers without radial displacement. This is accomplished by the film running in the rim of the idler wheels which are provided with a slightly raised 85 flange on the rim sides. Between the first two buffers is supported a second and driven feed sprocket 5^a which is of a larger diameter than the sprocket 5 and comprises the first of two such devices which feed the film 90 through the machine. Mounted on opposite sides of the sprocket 5^a are a pair of tension rollers 8^c and 8^d under which the film extends, thus maintaining it taut over the sprocket. To further insure an uninterrupted 100 pull on the film by the sprocket a movable and third tension roller 8^e is employed to maintain the film feed true relative to the sprocket. Between the last two idler wheels 10^a and 10^b is arranged another tension roller 8^f over which the film passes. This last named tension roller together with the feed sprocket 5^b positioned on the other side of the wheel serves to maintain the film 105 in proper buffing relation relative to the last 110 buffer 9^b. Inasmuch as some measuring device such as the cyclometer 11 is desirable to

indicate the feet of film treated the spindle for the feed sprocket 5^b offers a convenient means for driving the same. From the feed sprocket 5^b the film extends over still another feed sprocket 5^c which is driven as is the sprocket 5^a. This sprocket 5^c is also associated with a pair of tension rollers 8^g and 8^h the former being movable. Although all of the sprockets co-operate to feed the film through the machine only the sprockets 5^a and 5^c are driven, the other being more or less idler sprockets in that while they are mounted with freedom of rotation they are rotated only by the travel of the film over them. From the feed sprocket 5^c the film is delivered to a reel supported in the receiving magazine 4, the film entering the magazine through a radial slot in the magazine rim which is provided with a pair of opposed rollers 4^d between which the film is fed. Both magazines 3 and 4 are equipped with hinged covers.

With the general arrangement and co-operative relationship of the parts thus described the driving means will now be explained. This part of the invention represents one of the principal features of the machine in that it provides a practical method of feeding with film through the machine. The drive may be transmitted through the belt 12 to a master driving wheel 13 fixed to the horizontal shaft 14 which is journaled in the bearings 15 and 15^a, the latter being preferably a ball bearing. The opposite end of the shaft 14 provides a mounting spindle for the buffer 9^b and on which this buffer is fixedly mounted. Fixed to the shaft 14 approximately in the middle thereof is a worm gear 16 which is in mesh with a driven gear 16^a mounted in the middle of the shaft 16^b which shaft extends diagonally of the machine with its opposite ends provided with beveled gears 17 and 17^a which are in mesh with like gears 17^c and 17^b fixed to the ends of the spindles 18 and 18^a of the feed sprockets 5^a and 5^b respectively. The ends of the shaft 16^b are suitably journaled as at 16^c and 16^d. In this construction the drive transmitted to the wheel 13 and the worm 16 may be employed to rotate the feed sprockets 5^a and 5^b. Mounted coaxially on the shaft 14 are a pair of drive wheels 19 and 19^a, the former adapted to impart rotation to the buffer 9^b through the belt 19^b connecting the driven wheel 19^c which in turn is mounted on the buffer spindle. The driving wheel 19^a by means of the belt 19^d connecting the same in driving relation to the driven wheel 19^e mounted on the spindle of the buffer 9^b is adapted to impart the necessary rotation to the said buffer. Also mounted on the spindle of the buffer 9^b coaxially with the wheel 19^e is a driving wheel 20 for imparting the necessary rotation to the reel sup-

ported in the receiving magazine 4, this being accomplished by means of a wheel 20^a on the spindle of the magazine and the belt 20^b connecting the wheel 20^a in driving relation with the wheel 20. In order to impart rotation to the moistening rollers 6 the spindles of the rollers are provided with driven wheels 21 and 21^a connected in driving relation by means of a belt 21^b, a master drive wheel 21^c mounted coaxially on the spindle with the wheel 21^a and in driving relation with the small wheel 20^d on the spindle of the buffer 9, thus rotation of the buffer will impart the necessary rotation to the moistening rollers.

From the above description it will be readily seen the film may be supplied from the reel rotatably mounted in the magazine 3 and fed over the moistening rollers 6 where it will be supplied with necessary cleaning fluid and then fed in contact with a plurality of buffers and thence after being measured by the cyclometer 11 back to a second reel which is so driven to wind the film thereupon.

The detail construction of the parts forming the principal features of the invention will now be described. With reference to the moistening rollers attention is particularly invited to Fig. 6 which illustrates one of the moistening rollers in detail. Each of the rollers comprises a hollow drum having a perforated rim with a layer of absorbent material overlying the perforations in the rim. Cleaning fluid is fed from a sight feed chamber 6^a through a tube 6^b which terminates within the hollow drum whereupon the fluid may be deposited in the drum and absorbed by the layer of absorbent material over which the film is fed. A cup shaped device 6^c is supported beneath each of the rollers 6 to catch any excessive amount of the fluid which may be supplied to the drum. The drums are removably secured to their respective spindles by means of the threaded heads 6^d.

With reference to the detailed construction of the feed sprockets attention is called particularly to Fig. 7 wherein it will be seen that each of the sprockets both those that drive the film and those that are driven by the film comprise a substantially solid spool having an axial opening 5^e to receive the spindle on which they are mounted. The sprockets 5^f thereof which are mounted on opposite edges of the spool are replaceable in order that a new sprocket may be replaced for a worn one without discarding the entire spool. To accomplish this each side of the spool is adapted to receive a sprocket which is nothing more than an annular ring with peripheral teeth with openings in the side thereof adapted to register with openings in the side of the spool in order that suitable set screws 5^g may co-

operate with annular rings 5^h to confine the sprockets on the spool.

Referring now to the detail construction of the buffers, see particularly Fig. 5, in which each of the buffers are illustrated as comprising a hub 9^e having a series of radial slots in the rim thereof, each slot being adapted to receive the folded end of a felt strip 9^a, the opposite ends of the strip being positioned to contact with the surface of the film and act upon the same to clean and polish it. To confine the folded end of the strips in the slots pins are used to longitudinally engage the slots and wedge the folded end of the strips therein. In this construction if need be the length of the strips may be adjusted or regulated by releasing the pins and pulling one of the free ends of the strips beyond its adjacent end. The hub 9^e is provided with an axial opening for mounting the buffer on its respective spindle and when mounted the same is confined between the confronting faces of a pair of disks 9^e and 9^f of a diameter sufficient to completely close the hub but to leave the ends of the strips exposed. The buffers may be introduced upon their spindles and moved therefrom by the threaded heads 9^g.

The idler wheels 10, 10^a and 10^b may be also removed from their respective spindles by threaded heads 10^c.

The journal bearings are specially constructed in that they are self lubricating to which end special wooden sleeves are used throughout which will do away with the necessity of oiling the bearings.

Inasmuch as the film is fed from a reel supported within the delivery magazine 3 it will not be necessary to connect any driving means to the spindle thereof in order to obtain an even feed of the film. A frictional device is associated with the spindle (see Fig. 9) which comprises a pair of disks coaxially disposed on the spindle with a coil spring confined between an adjustable threaded head adapted to maintain the disks in frictional contact, the head being as stated adjustable to increase or decrease the

friction. The same arrangement is provided on the spindle of the receiving magazine. 50 However, in this instance a drive is imparted to the spindle which will necessitate enlarging the diameter of the friction disk and also increasing the tension of the spring. 55

I claim:

1. In a film cleaning and polishing machine, a frame, a cleaning and polishing means mounted in the frame and including a plurality of buffer wheels and idlers above said wheels, a sprocket wheel between two of the buffer wheels, a sprocket wheel at the rear of the frame, a driven shaft on which one of the buffer wheels is mounted, said shaft having a worm thereon, an inclined shaft having a worm wheel meshing with 60 the worm of the driven shaft, gears between the ends of the inclined shaft and the shafts of the sprocket wheels, and means for operating the other buffer wheels from said driven shaft. 70

2. In a film cleaning and polishing machine, a frame, a plurality of buffer wheels mounted in the frame, an idler above each buffer wheel, a sprocket wheel between two of the buffer wheels, a driven shaft on which one of said buffer wheels is mounted, a sprocket wheel at the rear of the frame, a shaft geared intermediate of its ends with the driven shaft, and at its ends with the said sprocket wheels, and means for operating the other buffer wheels from the driven shaft. 75

3. In a film cleaning and polishing machine, a frame, a plurality of buffer wheels mounted in the frame, an idler above each 80 buffer wheel, a sprocket wheel between two of the buffer wheels, a sprocket wheel at the rear of the frame, a driven shaft upon which one of the buffer wheels is mounted, means for operating the other buffer wheels 85 from the driven shaft, a gearing between the driven shaft and the said sprocket wheels, film spools, and means for operating one of the spools directly from one of the buffer wheels. 90

CHARLES RUDOLPH CARLETON.
